SEED MEASURING CUP FOR USE WITH CROP PLANTERS

Ralph E. Kunze, Columbus, Ohio, assignor to The Farm
Bureau Cooperative Association, Inc., Columbus Ohio,
a corporation of Ohio

Filed May 9, 1966, Ser. No. 2,220

Term of patent 14 years

(Cl. D35—2)

FIGURE 1 is a perspective view of a seed measuring cup for use with crop planters;

FIGURE 2 is a sectional view taken along line 2—2 of FIGURE 1;

FIGURE 3 is a plan view of the cup; and

FIGURE 4 is an end elevational view of the cup.

I claim:

The ornamental design for a seed measuring cup for use with crop planters, substantially as shown.
